PENCIL SHARPENER

Jay J. Lucas, Centerline, Mich., assignor of
twenty-five per cent to Ivan Elenbaas, Center-
line, Mich.

Application May 3, 1944, Serial No. 533,911

1 Claim. (Cl. 120—93)

The present invention relates to a novel and improved pencil sharpener of a type especially constructed and fashioned to be carried in one's pocket, the same being designed to utilize a so-called single-edged "Gem" type safety razor blade.

In reducing the principles of the invention to practice, I have perfected a construction and association of parts such as provides for correctly mounting and clamping the safety razor blade in position, whereby the cutting edge thereof is in correct adjustment and relation to the tapered adapter socket, this for reliable sharpening of pencils.

More specifically, the construction is characterized by a simple and economical substantially rectangular body, the same having the upper face of one longitudinal edge portion expressly rabbeted to define a blade seating and stabilizing platen and a downwardly stepped shoulder serving as a ledge for the reinforced backing element of the "Gem" blade, and this arrangement serving to accommodate a shouldered clamping plate to adequately coat with the blade in retaining the same removably in place.

Other features and advantages will become more readily apparent from the following detailed description and the accompanying illustrative drawing.

In the drawing, wherein like numerals are employed to designate like parts throughout the views:

Figure 1 is a perspective view of the complete pencil sharpener, constructed in accordance with the principles of this invention and ready for use.

Figure 2 is a view like Figure 1 with the detachable parts separated and spaced from one another to bring out the construction and arrangement of coordinated features.

Figure 3 is a top plan view of the assemblage seen in Figure 1.

Figure 4 is a longitudinal sectional view on the plane of the line 4—4 of Figure 3, looking in the direction of the arrows.

Figure 5 is a central transverse section taken approximately on the plane of the line 5—5 of Figure 1, looking in the direction of the arrows.

Although the device may be constructed of wood or other suitable material, it is preferably constructed from transparent materials such as may be appropriately colored or made transparent in order to enhance the appearance and utility, that is, from the standpoint of durability and lightness in weight. The main part of the

device is a substantially block-like or rectangular body 6 of appropriate dimensions. This is formed through one end with a tapered or conical bore 7, somewhat of conventional character and form, this to accommodate the pencil (not shown). A slot 8 opens into the top of the bore to discharge the shavings, as is customary. That edge 9 of the body which coacts with the slot is rounded off and merges into the slot for sake of utility as well as design. As before indicated, one longitudinal edge in the adjacent median portion of the body is rabbeted out, this to define a flat smooth platen 10, a step-down ledge 11 and upstanding end flanges or walls 12.

As before indicated, this device is expressly designed and otherwise constructed to accommodate a single-edged "Gem" safety razor blade. The body 13 of the blade is slightly wider than the underlying plate or supporting surface 18 on which it rests. The rigid backing 14 seats neatly on the ledge 11 and the cutting edge 15 projects into the slot 8 and the pencil reception socket 7. The clamping plate 16, which is of appropriate thickness and dimension is apertured and secured down on the body or base by a knurled fastening screw 17. The screw pierces the clamping plate and is threaded into a socket in the base. The plate has its outer edge formed with a channel which receives and accommodates the blade backing member 14. The opposite inner edge of the plate is curved as at 9a to coat symmetrically and otherwise with the aforementioned curvate edge or surface 9 (see Figure 5). The plate 16 fits snugly between the upstanding flanges or walls 12 and thus, all of the parts coact intimately to provide an efficient structural assemblage.

As previously mentioned, this type of sharpener is designed to utilize discarded safety razor blades, more especially those of the single-edged "Gem" type, the portions coacting with the blade in such a manner that the cutting edge is properly presented for keenly cutting the wood and sharpening the pencil. When the blade becomes too dull for continued use it is readily removed and another one is substituted therefor.

The invention is characterized by simplicity in construction and arrangement of parts, is extremely light in weight, insures keen cutting results, and is otherwise aptly fitted for the purposes intended. Incidental matters, such as dimensions and precise fitting together of parts will, of course, be scientifically established by the manufacturer, this, in order to insure reliable results at all times.

It is thought that persons skilled in the art to which the invention relates will be able to obtain a clear understanding of the invention after considering the description in connection with the drawing. Therefore, a more lengthy description is regarded as unnecessary.

Minor changes in the shape, size and arrangement of details coming within the field of invention claimed may be resorted to in actual practice, if desired.

Having described the invention, what is claimed as new is:

A pencil sharpener of the class described comprising a substantially rectangular body provided with a conical pencil accommodation socket 15 closed at one end and opening at its opposite

end through a corresponding end of the body, said body being formed in its top with a slot for registry with said socket, the body also having its major top portion rabbeted out to define a flat smooth blade accommodation platen, and a ledge along the outer longitudinal edge of said platen, the end portions of the body in alignment with said platen projecting to elevations above the surface of the plate to define abutment flanges, and a grooved clamping plate arranged between the flanges and overlying the plate and ledge, the outer edge of said clamping plate having a groove in alignment with and above said ledge.

JAY J. LUCAS.
